UNITED STATES PATENT OFFICE

92,160

DESIGN FOR A POWDER CONTAINER

Enoch Norris Brown, Philadelphia, Pa., assignor
to Lenthalic Incorporated, New York, N. Y., a
corporation of New York

Application February 28, 1934, Serial No. 50,898

Term of patent 14 years

To all whom it may concern:

Be it known that I, ENOCH NORRIS BROWN, a citizen of the United States, residing at Philadelphia, Pennsylvania, have invented a new, original, and ornamental Design for a Powder Container, of which the following is a specification, reference being had to the accompanying drawing, forming a part thereof.

In the drawing:

Figure 1 is a top plan view of a powder container showing my new design;

Figure 2 is a front elevation thereof; and
Figure 3 is a side elevation thereof.

The white stripes on the black areas and the black lines on the white areas indicate high lights, and are not a part of the design.

I claim:

The ornamental design for a powder container substantially as shown and described.

E. NORRIS BROWN,
